Inventor:
Christian Hultgren,
By J. Daniel Stuwe
Attorney.

UNITED STATES PATENT OFFICE.

CHRISTIAN HULTGREN, OF PARISH OF SVINHULT, SWEDEN.

TONE POST.

Application filed January 27, 1927, Serial No. 163,960, and in Sweden February 18, 1926.

My invention pertains to improvements in tone posts, especially such as are used in violins and similar stringed instruments; and the main object of the invention is to provide a new and improved tone post whereby any unevenness of tone and deficiency of any of the strings is overcome, and a surprisingly new and mellow effect of tonal quality is gained. Another object is to provide such a tone post which can be inserted in or applied to the instrument without substantially reconstructing or modifying the same.

These and other objects and advantages are attained with my invention, as will become apparent from the following description, taken in connection with the accompanying drawing, in which,

Fig. 1 is a top plan view of a violin with my invention applied thereto;

Fig. 2 is a longitudinal vertical section, taken through the median line of the violin and showing the tone post mounted therein;

Fig. 3 is a cross-sectional view through the violin, taken on line 3—3 of Fig. 1;

Figs. 4 and 5 are elevational views of the tone post; and

Fig. 6 is a plane view of the tone post.

My improved tone post consists of a hollow tube 8 made of selected wood, and having provided near one end thereof one or more holes, preferably in the form of cutouts or notches 9 placed at the end. This tone post is mounted between the back wall 10 and the front

wall 11 of the violin or instrument, preferably between the "f" holes 12, adjacent the bridge 13, and beneath the strings 14. The post is arranged so that the notch 9 is turned or directed toward the "f" hole, and placed under the front wall 11. Said post may also be slightly inclined forward toward said "f" hole, as indicated in Fig. 3, and the size of the post and of the notch can vary, according to the size and condition of the instrument.

What I claim as new and desire to secure by Letters Patent is:

1. A tubular tone post adapted to be interposed between the front and rear walls of a violin and having a single notch provided at its upper edge, turned toward the "f" hole of said violin.

2. A tone post adapted to be interposed between the front and rear walls of a violin said post consisting of a tube with slanting ends and having a notch provided at its upper edge adjacent said front wall, to be directed toward one side of said violin.

3. In combination with a violin, a tubular tone post interposed between the front and rear walls of said violin and having a single notch, provided at its upper edge, said notch being directed toward one side of the violin and said post being slightly inclined with said notch forward toward said side.

In testimony whereof I have signed my name to this specification.

CHRISTIAN HULTGREN.
